UNITED STATES PATENT OFFICE.

HENRY BAETZ, OF ST. LOUIS, MISSOURI, ASSIGNOR TO SKINNER BROS. MFG. CO., OF ST. LOUIS, MISSOURI, A CORPORATION OF MISSOURI.

VENTILATION.

Application filed March 13, 1925. Serial No. 15,383.

To all whom it may concern:

Be it known that I, HENRY BAETZ, a citizen of the United States, residing at St. Louis, in the State of Missouri, have invented certain new and useful Improvements in Ventilation, of which the following is a specification.

My invention has relation to improvements in heating and ventilating and consists of the novel features of construction and arrangement more fully set forth in the specification and pointed out in the claim.

The object of the present invention is primarily to heat and ventilate large buildings, such as factories, wherein the gases, odors, and fumes incident to the manufacturing carried on within the building may be quickly and continuously vented by the combined action of ventilating devices with the heating apparatus. Of course, in mild weather when the building does not require heating, the ventilating devices alone are necessary.

A further object of the invention is the effecting of a rapid and continuous exchange of the vitiated atmosphere for fresh, clean air without the production of well defined air currents, as these are harmful to the carrying on of certain operations, such as painting, where a smooth, even coat, unspoiled by dust, is required. Further advantages of the invention will be better apparent from a detailed description of the invention in connection with the accompanying drawings, in which—

Figure 1 is a floor plan, more or less diagrammatic, showing the general arrangement of heaters and ventilators, in a building; Fig. 2 is a vertical longitudinal section taken on the line 2—2 of Fig. 1 with parts broken away; Fig. 3 is a vertical cross-section through the building taken on the line 3—3 of Fig. 1; Fig. 4 is a sectional detail of the cowl of a ventilator.

Referring to the drawings, B represents a building consisting, in the present case, of three floors, F, F', F'', the 2nd and 3rd floors F', F'', being supported, as well as the roof R by a number of columns 1, 1, 1 etc. in proper spaced relation. On one side of the building (or in cases of very large buildings, more than one side) may be built a pent-house 2 in which there is placed air-

heating devices 3, 3', 3'' for the respective floors.

Each heater is provided with a fan or blower b for forcing the heated air into the building.

The respective air-heating devices have hot air outlets 4, 4', 4'' extending through the building wall and arranged to discharge heated air into the rooms above the respective floors.

For drawing off the vitiated air from the respective floors, I provide a plurality of ventilating units V distributed over the entire floor area and uniformly spaced, these units being mounted, in the present case, on alternate pillars 1, 1', 1'' and extending up through the roof R. Each ventilating unit consists of three conduits 5, 5' and 5'', conduit 5 having its lower open end extending down to near the ground floor F, conduit 5' terminating just above the 2nd floor F', and conduit 5'' terminating just above the 3rd floor F''. The three conduits, however, are integrally formed (preferably) and open at their upper ends into a casing 6 having a revolving ventilator cowl 7 mounted on it. Thus the one casing 6 and cowl 7 serve the three conduits 5, 5', 5'' and the assembly of these parts constitutes but a single ventilating unit which serves all three floors.

The distribution of the ventilators over the entire floor area in substantially uniformly spaced relation insures the rapid voiding of odorous gases, and prevents the formation of drafts or air currents by reducing to a minimum the distance the vitiated air must travel before being voided. In other words the large floor area is subdivided into a large number of zones for the purpose of ventilation, such as those defined by the dotted circles lettered a in Figure 1, and the small amount of air to be exhausted from any one zone requires so little draft through its particular ventilator that well defined air currents are not set up. It is extremely important to avoid these well defined air currents since they greatly interfere with the production of a satisfactory product, where particular drying and treating operations are involved.

Communicating with the inside of the building above each floor and the pent-house 2 is a damper 8, and in an outer wall

of the pent-house, is a damper 9. When it is desired to force fresh air into the building the damper 8 is closed and the damper 9 opened, and when it is desired to recirculate the air within the building the damper 8 is opened and the damper 9 closed.

Each conduit 5, 5', 5'' is provided with a gate 10 near ceiling of the room and said gate when opened is adapted to shut off that part of the conduit below it. The function of this gate 10 is to provide an alternate outlet for the noxious gases in the room when they are of such character that they adhere to the upper part of the room.

In the operation of the invention the heaters 3, 3', 3'' are put into operation, and their fans *b* started so as to force fresh, heated air into the rooms. At the same time the fresh, warm air is entering, the vitiated air will be exhausting through the ventilator conduits as above described. Obviously, if desired, the heaters may be used merely as air supplying devices without first heating the air, or they may be dispensed

with entirely when outdoor conditions are favorable to taking the fresh air into the building through the windows.

Having described my invention I claim:

In a ventilating system, the combination with a room to be ventilated, of a pent-house adjoining said room, a valve-controlled opening between the pent-house and said room and a valve controlled opening between the pent-house and the outdoors, an air-moving device within the pent-house and having an air outlet directed toward said room, and a plurality of ventilating units uniformly distributed over the floor area of said room, each of said ventilating units comprising an air receiving conduit and an air-discharge cowl mounted at the top thereof, and said receiving conduit having two air intake openings in spaced relation, and means for closing either of said intake openings.

In testimony whereof I hereunto affix my signature.

HENRY BAETZ.
